UNITED STATES PATENT OFFICE.

ROBERT A. FORESMAN, OF ESSINGTON, PENNSYLVANIA, ASSIGNOR TO WESTINGHOUSE ELECTRIC AND MANUFACTURING COMPANY, A CORPORATION OF PENNSYLVANIA.

TUYÈRE STRUCTURE FOR STOKERS.

Application filed June 30, 1920. Serial No. 393,018.

To all whom it may concern:

Be it known that I, ROBERT A. FORESMAN, a citizen of the United States, and a resident of 21 Jansen Ave., Essington, in the county of Delaware and State of Pennsylvania, have invented a new and useful Improvement in Tuyère Structures for Stokers, of which the following is a specification.

10 This invention relates to stoker structures and more particularly to that class of underfeed stokers employing alternately disposed retorts and inclined tuyères, and it has for its object the provision of an improved air-cooled locking member which is simple in construction and which affords no place for fuel lodgment.

15 Another object is to provide a locking member which affords an ample air passage through which air may be freely delivered from the tuyère boxes to the air distributing box, thus insuring the delivery of ample quantities of air to the distributing box, but, at the same time, preventing 20 overheating of the locking member or the formation of clinkers adjacent the air delivery box.

These and other objects are attained by means of a locking member embodying the 30 features herein described and illustrated in the drawings accompanying and forming a part hereof, wherein;—

Fig. 1 is a transverse section on the line I—I of Fig. 2 through an underfeed furnace and stoker in the vicinity of the front wall.

Fig. 2 is a transverse section of the construction taken on the line II—II of Fig. 1.

Referring to the drawing, the stoker includes a series of fuel hoppers 5 mounted adjacent the front wall 6 of the furnace. Each hopper is provided with a discharge outlet 7 through which fuel is forced into the retort aligned therewith by means of a 40 ram 9 which reciprocates within the bottom section of the hopper. As shown, each retort consists of a bottom portion 10 and side walls 11 forming a fuel trough which extends longitudinally of the furnace.

50 Tuyère blocks 12 are mounted in overlapped relation on the adjacent sides of adjacent retorts, the said sides being spaced apart to form a tuyère box 14 between adjacent retorts which is in open communica-

cation with an air box 28 formed beneath the retorts.

An air distributing box 15 provided with an air space 16 extends entirely across the width of the furnace and supports the front wall 6 thereof. This box is provided adjacent the front wall with a row of inwardly-directed tuyère openings 15' through which air is distributed to the fuel near the front wall of the furnace.

The usual practice has been to support 65 the air-distributing box upon the forward ends of the retorts or upon the hopper castings, and to supply it with air through ports in the upper portion of the tuyère box. The available space at the point of connection 70 of the air distributing box with the tuyère box is frequently limited so that adequate air passages cannot be provided for conducting air from the tuyère box to the air-distributing box. In order to obviate this 75 difficulty, I provide hollow locking members 17 which are adapted to be mounted upon the uppermost tuyère blocks 12 so as to prevent vertical displacement thereof. Lateral displacement of the tuyères is prevented by the dowel pins 18 projecting upwardly from sockets 19 provided in the 80 upper faces of the top tuyères, and engaging slots 19' in lower faces of the locking members 17.

85 Each locking member is provided with an air space or passage 20 which receives air from a tuyère box through a passage 21 which is formed by suitable notches in the forward ends of the uppermost tuyère blocks.

90 The forward face of the locking member is set at an angle corresponding to the adjacent rear face of the air-distributing box 15 and is provided with a discharge orifice 22 surrounded by a neck or collar 23 which projects into the air space 16 in the air-distributing box through an orifice 24. The space between the front face of the locking member and the adjacent rear face of the air-distributing box is closed by means of a suitable packing which is tightly compressed when the locking member is drawn 100 into operative position toward the air-distributing box by suitable bolts 25. The bolts 25 are inclined with respect to the top face of the member and are fastened to the flanges 26 of the tuyère boxes in such 105

manner that when the nuts 27 are tightened, the locking members are drawn downward and toward the air-distributing box, thus making an air-tight joint between the air distributing box and the locking members.

The advantage of this construction resides in the fact that ample air passages through which air may freely pass to the air-distributing box are made possible and 10 that the locking members are cooled by contact with the cool air passing through them. Where it has been the practice to provide solid locking crowns through which no air is circulated, particularly with flat upper 15 surfaces, fuel has tended to lodge thereupon and to smolder because of insufficient air. As a result, objectionable smoke has formed and leaked out into the fire-room. With the proposed structure, the fuel tends 20 to slide off from the locking member rather than to lodge thereupon, and all fuel in passing over this portion of the grate is subject to active combustion and strong draft so that the leakage of smoke into the 25 fire-room is effectually prevented.

While I have described and illustrated but one embodiment of my invention, it will be apparent to those skilled in the art that various changes, modifications, additions, and 30 omissions may be made in the apparatus described without departing from the spirit and scope of the invention as set forth by the appended claims.

What I claim is:—

35 1. A stoker construction comprising an air distributing box extending across the furnace adjacent the front wall thereof, tuyère boxes extending longitudinally of the furnace, tuyères mounted on the tuyère boxes 40 and receiving air therefrom, locking members for securing the tuyères in position mounted upon the uppermost tuyères and disposed adjacent the air distributing box, and means for establishing communication 45 from the tuyère boxes to the distributing box, through the said locking members.

50 2. A stoker construction comprising an air distributing box extending across the furnace adjacent the front wall thereof, tuyère boxes extending longitudinally of the furnace, tuyères mounted on the tuyère boxes and receiving air therefrom, locking means for the tuyères disposed adjacent the air distributing box, and means for passing air 55 from the tuyère boxes to the air distributing box through the said locking means.

60 3. A stoker construction comprising an air distributing box extending across the furnace adjacent the front wall thereof, tuyère boxes extending longitudinally of the furnace, tuyères mounted on the tuyère boxes and receiving air therefrom, locking members for the said tuyères disposed between

the said air distributing box and the said tuyères establishing communication between 65 the said air distributing box and the said tuyère boxes; and refractory packing between the said locking members and the air distributing box.

4. A stoker construction comprising an air 70 distributing box extending across the furnace adjacent the front end thereof, tuyère boxes extending longitudinally of the furnace, tuyères mounted on the tuyère boxes and receiving air therefrom, locking members disposed between the tuyères and the air distributing box adapted to engage the uppermost tuyères to prevent vertical and lateral displacement of the latter, each of the said locking members being provided with an air delivery neck and the said distributing box with cooperating openings through which said necks project, packing disposed 75 between the locking members and the said air distributing box and surrounding said necks, means for drawing the locking members into contact with the said tuyères and with the said packing, and means for delivering air to the said distributing box.

5. A stoker construction comprising an air 80 distributing box, tuyère boxes disposed adjacent the air distributing box, tuyères mounted on the tuyère boxes and receiving air therefrom, locking members disposed between the tuyères and the air distributing 85 box adapted to engage the uppermost tuyères to prevent vertical displacement of the latter and receive air from the said tuyère boxes, each of the said locking members being provided with an outlet orifice 90 and said air distributing box with cooperating orifices registering with said outlet orifices, whereby air may pass from the tuyère boxes to the air distributing box.

6. A stoker construction comprising an 95 air distributing box, tuyère boxes disposed adjacent the air distributing box, tuyères mounted on the tuyère boxes and receiving air therefrom, locking members disposed between the tuyères and the air distributing 100 box adapted to engage the uppermost tuyères to prevent vertical displacement of the latter and receive air from the said tuyère boxes, each of the said locking members being provided with an outlet orifice and said air distributing box with cooperating orifices 105 registering with said outlet orifices, packing between the said air distributing box and the said locking members, and means for drawing the locking members into contact with the said distributing box and with the said packing.

In testimony whereof, I have hereunto 110 subscribed my name this 22nd day of June, 1920.

ROBERT A. FORESMAN:
